PNEUMATIC TIRE

Marcia G. Mylor and Frederick W. Hertzler, Detroit,
and Dominic A. Saporito, Royal Oak, Mich., assignors
to United States Rubber Company, New York, N. Y.,
a corporation of New Jersey

Application March 22, 1954, Serial No. 29,632

Term of patent 14 years

(Cl. D90—20)

Fig. 1 is a side elevational view of a pneumatic tire showing our new design; and

Fig. 2 is an enlarged sectional and fragmentary perspective view taken on the line II—II of Fig. 1.

Our design for the pneumatic tire shown is characterized by the configuration and appearance of the side wall thereof which comprises a relatively narrow substantially white side wall zone adjacent the tire bead surrounded by a relatively dark side wall zone extending to the tire tread; the outer boundary of the white side wall zone being inwardly stepped with relation to the surface of the adjacent surrounding dark side wall zone.

We claim:

The ornamental design for a pneumatic tire, substantially as shown and described.
